THERMOSTATIC CONTROL SWITCH

Axel Christensen, Racine, Wis.

Application June 24, 1937, Serial No. 150,128

3 Claims. (Cl. 200—137)

This invention appertains to control devices, and more particularly to a thermostatically regulated control switch capable of general application, and particularly adapted for use in conjunction with boilers having oil burners, stokers, and the like.

One of the primary objects of my invention is to provide a control device of exceptionally simple and durable construction, one that will be sensitive to temperature changes, and one which can be easily and quickly associated directly with the appliance to be controlled. Another salient object of my invention is to provide an efficient mechanism for manually setting the switch to the temperature that is desired to be maintained, whereby the device will be capable of controlling a wide range of temperatures.

A further important object of my invention is to provide a control device embodying a mercury switch pivotally mounted at one end and an operating lever supporting the other end actuated from a heat sensitive expansion element for tilting the switch, with means for manually shifting the switch and lever bodily toward and away from said heat sensitive element, whereby to accurately control the throwing of the switch when a desired temperature is reached.

A still further object of my invention is to provide a control device in which wear will be reduced to a minimum and all lost motion eliminated.

With these and other objects in view, the invention consists in the novel construction, arrangement, and formation of parts, as will be hereinafter more specifically described, claimed, and illustrated in the accompanying drawing, in which drawing:

Figure 1 is a longitudinal sectional view through the improved control device.

Figure 2 is an end elevational view of the control device.

Figure 3 is an enlarged, detail sectional view taken on the line 3—3 of Figure 1, looking in the direction of the arrows, illustrating the means for rockably supporting the actuating lever.

Figure 4 is an enlarged, fragmentary, detail sectional view taken substantially on the line 4—4 of Figure 1, looking in the direction of the arrows, illustrating the mounting of the mercury switch.

Figure 5 is a fragmentary, top plan view illustrating the mounting of the actuating lever and the mercury switch on the slide bar.

Referring to the drawing in detail, wherein similar reference characters designate corre-

sponding parts throughout the several views, the letter C generally indicates the improved control, which embodies a protecting housing or casing 10. The inner end wall of the casing has connected therewith a coupling nipple 11. The nipple 11 is in turn secured to the appliance 12, the temperature of which is to be controlled.

The appliance 12 in the present instance may be considered as a hot water boiler. The horizontally extending bore 13 of the nipple 11 is enlarged at its inner end, as at 14, and this portion of the bore receives and supports the heat responsive means 15.

The heat responsive means 15 includes a tube 16 formed from a metal possessing a high coefficient of expansion and an inner rod 17 formed from a material having a low coefficient of expansion. The rod 17 is anchored to a head 18 rigidly connected to the inner end of the tube, and the rod 17 extends through the bore 13 and 20 into the casing 10.

Rigidly secured to the lower wall of the casing 10 is a longitudinally extending U-shaped guide bracket 19, the legs 20 of which are apertured for slidably receiving a slide bar 21. The outer end 25 of the slide bar 21 has anchored thereto, by means of a cross-bar 22, upstanding arms 23. The arms 23 in turn support pivot pins 24 on which is rockably mounted a supporting plate 25. Secured to the plate 25 by means of a suitable clip 26 is a tube or bulb 27 having a globule of mercury 28 or other electric conducting material therein. The plate and bulb extend inwardly of the pins 24 and hence, in effect, the bulb is rockably mounted at its outer end. This end 35 has anchored therein a pair of spaced contacts 29 to which are connected electric wires 30. The electric wires 30 are in turn connected by means of binding posts 31 to spaced conducting plates 32, to which are secured conductor wires 33 leading to a source of electrical energy and the device to be controlled, such as an electric motor of an oil burner or a coal stoker.

Obviously, when the inner end of the bulb 27 is in a lowered position, the globule of mercury 45 28 rides away from the contacts 29 to open a circuit, and when the inner end of the bulb is in an elevated position, the globule of mercury will bridge the contacts 29 and close a circuit.

The forward end of the slide bar 21 has anchored thereto the forwardly extending bracket 34 on which is rockably mounted the forward end of the actuating lever 35. The lever 35 extends toward the front of the casing from its pivot pin and terminates in an upwardly curved 55

bearing head 36 on which rests the plate 25 carrying the bulb. The inner end of the actuating lever has formed thereon or secured thereto a depending bearing lip 37, which extends below the pivot for the lever, and this lip is adapted to engage the end of the operating rod 17, which extends into the casing.

Manual means is provided for shifting the slide rod 21, whereby the position of the lever 35 and the bulb 27 can be varied relative to the operating rod 17. The means for manually shifting the position of the slide bar 21 includes an operating shaft 38. This shaft 38 is rotatably mounted in a suitable bearing 39 carried by a removable portion 40 of the casing. The outer end of the shaft 38 has firmly secured thereto a dial disc 41 and an operating knob 42. The dial disc is graduated in the desired manner, and a pointer 43 for cooperating with the dial disc is carried by the casing.

Secured to the inner end of the operating shaft 38 is an elongated spur gear 44, which has constantly meshing therewith a relatively thin spur gear 45. The spur gear 45 is of a greater diameter than the spur gear 44, and is formed on or secured to a traveling screw 46. This screw 46 is threaded into a guide sleeve 47 carried by the casing. A suitable bearing knob 48 is carried by the screw 46 and bears against the outer end of the slide rod. The slide rod is normally held in contact with the bearing knob 48 at all times by a contractile coil spring 49. The opposite ends of this spring are suitably anchored to the slide bar 21 and to the bracket 19.

From the description so far, it can be seen that upon the turning of the shaft 38 by the knob 42, the screw 46 will be moved in or out, which will bring about the shifting of the slide bar. This shifting of the slide bar will vary the position of the actuating lever 35 relative to the operating rod 17.

In use of my improved device, the knob 42 is turned until the dial disc travels to the temperature indicated on the disc, at which the heat is to be maintained. This brings about the initial adjustment of the lever 35. As the appliance 12 increases in temperature, the tube 16 will expand, and the head 18 will gradually draw the rod 17 away from the lip 37.

When a predetermined temperature for which the device is set is reached, the rod 17 will permit the inner end of the lever 35 to lower, and the bulb 27 will swing down, as shown in Figure 1. The globule of mercury will consequently roll away from the contacts 29. As the temperature lowers, the tube 16 will contract and the rod 17

will be gradually carried inwardly, which will swing up on the inner end of the lever 35, and when the bulb 27 is again raised to an elevated position, the globule of mercury will flow down the tube into engagement with the contacts. 5

The construction of my device is such that the operating lever 35 directly supports the mercury switch. This eliminates friction and lost motion, and upon manual adjustment, the lever and switch are synchronously moved toward and 10 away from the operating rod as a unit.

Changes in details may be made without departing from the spirit or the scope of my invention, but what I claim as new is:

1. In a control device of the character described, heat-responsive means movable upon temperature change, a slide bar, a control switch rockably mounted at one end upon the slide bar, an actuating lever movable by said heat responsive member rockably mounted on the slide bar, 20 and supporting said switch at a point remote from its pivot point, and means for varying the position of the slide bar.

2. In a control device of the character described, heat-responsive means movable upon temperature change, a longitudinally movable slide bar, a mercury switch rockably mounted at one end upon the slide bar, an actuating lever movable by said heat responsive means rockably mounted upon the slide bar and supporting said 30 mercury switch at a point remote from its pivotal connection, a traveling screw, spring means normally urging the slide bar into engagement with the traveling screw, and manual means including a dial and a pointer for rotating the 35 screw.

3. In a control device of the character described, heat-responsive means movable upon temperature change, a guide bracket, a slide bar mounted in said bracket and movable longitudinally toward and away from the heat-responsive means, a supporting plate rockably mounted upon the slide bar, a mercury switch on said plate, means detachably securing the switch to the plate, said switch projecting forwardly from 45 the pivot point of the plate, an actuating lever rockably mounted on the inner end of the slide bar including an elongated arm engaging the plate at a point remote from its pivot, and a depending short arm engaging a part of the 50 heat-responsive means, a traveling screw, spring means normally urging the slide bar into engagement with the screw, and manual means for turning the screw.

AXEL CHRISTENSEN. 55
